His attorney.

UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

ELECTRIC SOCKET.

1,247,820.

Specification of Letters Patent. Patented Nov. 27, 1917.

Application filed November 6, 1915. Serial No. 60,045.

To all whom it may concern:

Be it known that I, DAVID D. GORDON, a citizen of the United States, and a resident of Chicago, in the county of Cook and State 5 of Illinois, have invented a certain new and useful Electric Socket; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to electric sockets, and has for its object the provision, in a socket of this character, of a two-part insulating construction the parts of which are locked together in assembled relation by the 20 attaching of an incandescent lamp, a connecting plug, or other device thereto. Further objects and advantages of the invention will be apparent to persons skilled in the art.

25 The invention is fully described in the following specification, and while, in its broader aspect, it is capable of embodiment in numerous forms, a preferred embodiment thereof is illustrated in the accompanying drawings, in which,—

30 Figure 1 is a central longitudinal section of a socket of the brass-shell key type embodying my invention. Fig. 2 is a different longitudinal section of the socket with the 35 cap parts removed and with parts in full, and Fig. 3 is a side elevation of the socket with parts broken away.

35 Referring to the drawings, 1 and 2 designate the base and cap parts, respectively, of the insulating body of the socket, and 3 and 4 designate the body and cap portions, respectively, of the shell customarily employed in certain types of sockets. This shell, however, forms no part of the present 45 invention and may be eliminated from the socket without departing from the spirit of the invention, as the invention is contemplated for use both in the porcelain and brass shell types of sockets. The shell parts 50 are separably secured together in any suitable manner as is well understood in the art.

The customary center and side contacts for the attaching plug, lamp or other mem-

ber (not shown), are secured to the outer 55 end of the base part 1 of the insulating body and are designated 5 and 6, respectively. The side contact 6 is of the customary screw shell form and is provided in one side thereof with an opening 7, which extends outward from its inner end and is for the purpose hereinafter described.

The base and cap parts 1 and 2 of the insulating body coöperate, in the present instance, to form a closed, or insulatingly 65 closed, chamber 8 in which the terminal binding posts and switch mechanism, if such mechanism is employed, are preferably disposed. The lead wires 9 are intended to extend through registering openings 10 in 70 the cap parts 2 and 4 of the insulating body and shell and are connected by binding screws 11, one only of which is shown, to respective contact plates 12 and 13 secured within the chamber 8 to the inner side of the 75 cap 2. The contact plate 12 has a conductor finger 14 projecting therefrom lengthwise of the socket and in position to make contact with a conductor finger 15 secured to the insulating base part 1 within the chamber 8. 80 The conductor finger 15 is adapted, in the present instance, to have electrical connection with the center contact 5 of the socket through the medium of a bridging switch member 16 of any suitable form, which is 85 operable to make and break contact with the contacts 17 and 18, the former of which forms a part of or has electrical connection with the finger 15, while the latter forms a part of or has electrical connection with the 90 center contact 5. If a switch is provided to form the electrical connection between the contact finger 15 and center contact 5, as in the present illustration, such switch may be either of the key or pull-chain type and of 95 any suitable construction. As the form of switch shown is merely for illustrative purposes and forms no part of the invention, it will not be specifically described.

100 The contact plate 13 has a conductor finger 19 projecting therefrom lengthwise of the socket through a side portion of the chamber 8, thence through a registering opening 20 in the outer end portion of the insulating base part 1 and into the opening 7 of the side 105 or screw shell contact 6. The portion of the finger 19 which projects into the screw shell opening 7 is formed with screw threads,

as indicated at 21, which threads register with and form continuations of the threads in the screw shell 6 so that a lamp or other connecting member, when screwed into the shell 6, has threaded connection with the finger 19 and prevents a removal of the cap part 2 and a withdrawal of the finger 19 from the assembled position shown in Figs. 1 and 3. The threaded end portion of the finger 19 is preferably sprung slightly inward with respect to the screw shell wall so as to insure a perfect electrical contact between said finger and the side contact of the plug or other attachment. It will be understood that the screwing of a plug or other attachment into the shell 6 will force the threaded end portion of the finger 19 outward into circular register with the side walls of the shell opening 7. 22 designates an insulating sleeve which is disposed between the shell part 3 and screw shell 6, and may be integral with or made in a separate piece from the insulating body base 1.

It is evident that the interengaging of the conductor finger 19 with an attachment plug, or other device which is inserted into the screw shell 6, causes a firmer locking together of the base and cap parts 1 and 2 of the insulating body of the socket, thus preventing a removal of the base part 1 from operative connection with the cap until the plug or other attachment has been removed from the screw shell 6; and also that the screw shell may be eliminated entirely and the plug or other attachment, when inserted into the socket, engaged alone to the finger 19.

I wish it understood that the present embodiment of my invention is merely for illustrative purposes and that the invention is not limited to the particular arrangement and construction of parts shown but is capable of numerous modifications without departing from the spirit of the claims.

Having thus described my invention, what I claim as new, and desire to secure by Letters Patent, is—

1. In an electric socket, an insulating body having separable base and cap members, a screw shell and a center contact carried by said base member, terminal binding means carried by said cap member and having separable electrical connection with said center contact, and a second terminal binding means carried by said cap member and having a part projecting therefrom through a portion of said base member and into position to make side contact with an attachment screwed into said shell.

2. In an electric socket, an insulating body having separable base and cap members, a center contact carried by said base member, terminal binding means carried by said cap member and having separable electrical connection with said center contact and a second terminal binding means and a

conductor finger both carried by said cap member in electrical connection, said finger adapted to project through a part of said base member and to coact with the side contact of an attachment device, when inserted into the socket, to close the electric circuit and to secure the cap and base members in assembled position.

3. In an electric socket, an insulating body having separable base and cap parts, a center contact and a screw shell carried by said base member, said screw shell having an opening in a side thereof, double terminal binding means carried by said cap member and a contact part projecting from each of said binding means, one of said contact parts having separable electrical connection with said center contact and the other contact part projecting through said base member lengthwise of the socket and into the opening in said screw shell, the portion of said last mentioned contact part which projects within said shell opening being threaded to interengage and make contact with the threaded side contact of an attachment device when threaded into said shell.

4. In an electric socket, an insulating body having separable base and cap members, a screw shell having an opening in a side thereof, a center contact secured to the outer end of said base member, a contact secured to the inner side of the base member and having electrical connection with said center contact, a pair of contacts carried by said cap member at the inner side thereof and one having contact with the contact part on the inner side of said base member and the other projecting through said base member and into said shell opening when said base and cap members are in assembled position, the last mentioned of said cap contact parts having the portion thereof which projects within the shell opening threaded to interengage and make side contact with the threaded contact portion of an attachment device when threaded into said shell, and means for securing terminal wires to said cap contacts.

5. In an electric socket, an insulating body having base and cap members, a screw shell having an opening in its side and a center contact carried by the outer end of said base member, an interior contact carried by said base member and adapted to have electrical connection with said center contact, a pair of contacts carried by said cap member at the inner side thereof and one having a part which makes contact with the interior contact of said base member and the other of said contacts having a part projecting therefrom into said shell opening and having threads positioned to interengage with the threaded side contact of an attachment member when screwed into said shell, and when said base and cap members

are in assembled relation, said threaded contact part being normally sprung slightly inward with respect to said shell.

6. In an electric socket, an insulating body having separable base and cap members, a screw-shell, and a center contact carried by said base member, terminal binding means carried by said cap member and having separable electrical connection with said 10 center contact, and a second terminal binding means carried by said cap member and

having a spring conductor finger projecting therefrom through a portion of said base member longitudinally thereof and into position to make side spring contact with an 15 attachment screwed to said shell, said finger being adapted to interengage with the threaded portion of an attachment.

In testimony whereof, I have hereunto signed my name to this specification.

DAVID D. GORDON.
